UNITED STATES PATENT OFFICE

148,883

DESIGN FOR A SERVING TRAY FOR GLASSES OR THE LIKE

William C. Panzer, Chicago, Ill.

Application May 29, 1946, Serial No. 130,230

Term of patent 14 years

(Cl. D44—10)

To all whom it may concern:

Be it known that I, William C. Panzer, a citizen of the United States, residing in Chicago, Cook County, Illinois, have invented a new, original, and ornamental Design for a Serving Tray for Glasses or the like, of which the following is a specification, reference being had to the accompanying drawings, forming a part thereof.

Figure 1 is a top view of a serving tray for glasses or the like embodying my new design; Figure 2 is a side elevational view thereof; and Figure 3 is an end elevational view.

I claim:

The ornamental design for a serving tray for glasses or the like, substantially as shown.

WILLIAM C. PANZER.
